UNITED STATES PATENT OFFICE.

HARRY E. BROWN, OF AUGUSTA, KANSAS.

OIL-WELL JACK.

1,254,572.

Specification of Letters Patent. Patented Jan. 22, 1918.

Application filed May 5, 1917. Serial No. 186,690.

To all whom it may concern:

Be it known that I, HARRY E. BROWN, a citizen of the United States, and a resident of Augusta, in the county of Butler and State of Kansas, have invented a new and Improved Oil-Well Jack, of which the following is a full, clear, and exact description.

My invention relates more particularly to jacks for operating wrenches in coupling and uncoupling the drill rods of oil wells but is useful in connection with hoist or track jacks and other tools. With one known form of jack for example, in operating on drill rods, it is customary to apply 10 to the respective rod sections to be coupled or uncoupled, two wrench bars, and a curved rack bar or sector is fastened in position concentric with the drill rod. The wrench bars are engaged with the drill rod sections 20 at one end, the opposite end of one wrench bar being engaged against a permanent stop, while the other wrench bar is moved over the sector by a jack which includes a carriage and a lever, the lever actuating pawls 25 to advance the carriage and with it the movable wrench bar.

An object of my invention is to provide an improved lever mechanism for the jack whereby the leverage may be compounded 30 when desired, or adjusted to give direct action.

A further object of the invention is to provide a novel detachable brace for the sector.

The invention will be particularly explained in the specific description following. Reference is had to the accompanying drawings forming part of this specification, in which similar characters of reference indicate corresponding parts in all the views, 35 and in which:

Figure 1 is a plan view of an oil well jack to which my invention has been applied;

Fig. 2 is a vertical section on the line 2—2 of Fig. 1;

Fig. 3 is a vertical section of the jack taken at right angles to the line 2—2, and on an enlarged scale, showing a portion of the sector;

Fig. 4 is a section on the line 4—4 of Fig. 3;

Fig. 5 is a side elevation of the jack on a reduced scale with the lever mechanism adjusted as in Figs. 3 and 4; and

Fig. 6 is a sectional side elevation with

the lever mechanism adjusted differently from the positions shown in Figs. 3 and 4.

In Figs. 1 and 2 A, A¹ represent adjacent drill sections to be coupled or uncoupled; 60 10 represents one of the usual wrench bars having a head 11 to engage one drill rod section A¹, and 12 indicates the movable wrench bar having a head 13 to engage the adjacent drill rod section A. The wrench bar 10 at the end opposite the drill rod is 65 engaged with any fixed stop or shoulder 15 on the toothed sector 14, while that end of the movable wrench bar 12 opposite to the drill rod is engaged by the forward end of the jack carriage 16. 70

In my improved jack a lever 17 is employed and may include any approved socket removably receiving a handle 17^a. The lever 17 includes, furthermore, in accordance with my invention, an auxiliary lever 18 and the 75 two are arranged for joint movement as a unitary lever or for relative movement in compounding, as will appear. The fulcrum for the lever is obtained by a transverse pin 19 which passes through the auxiliary lever 80 or head 18 and the sides of the carriage 16, said carriage being longitudinally slotted as at 16^a to receive the lever. As is usual, the lever is equipped with a pair of pawls 20, 21, pivoted respectively as at 22, 23, to the 85 auxiliary lever 18 above and below the fulcrum pin 19, so that in the rocking of the lever the pawls will alternately engage the teeth of the sector 14. In order that the pawls 20, 21, have more reliable engagement 90 with the sector, they are formed as multiple dogs. Thus each pawl includes forked or double toothed dog 20^a integral therewith, and a single toothed dog 20^b pivoted between the teeth of the dog 20^a as at 20^c. 95

Similarly, the pawl 21 has an integral forked or double toothed dog 21^a thereon and a single dog 21^b pivoted between the teeth of the dog 21^a as at 21^c. The multiple dogs thus provided not only insure engagement 100 with the teeth of the sector at all times, but the strain is distributed between the several dogs, and the life of a pawl is thus prolonged, since the breaking of one dog or tooth does not throw the jack out of action. 105

In order to provide for the operation of the lever 17 and the auxiliary lever 18 as a unitary lever of the first class, or to provide for compounding the leverage by giving an indirect movement to the auxiliary 110

lever 18, connection between the respective lever members is effected as follows:

The auxiliary lever 18 is formed with a flaring socket 26 receiving the end of main lever section 17 and a transverse pin 24 is carried by the lever 17. Said pin has rollers 24^a at the ends which may roll in longitudinal slots 25 in the upper end of the auxiliary lever 18, the slots being oblique or inclined to the longitudinal axis of the lever to lessen the frictional engagement with the rollers. Below the pin 24 means is provided to variously connect the main lever section 17 and the auxiliary lever section 18, said means including a removable pin 27 adapted to be placed in two positions to connect the lever sections with each other and with the side walls or cheeks of the carriage 16. In Figs. 3, 4 and 5 the pin 27 is passed through holes 31 in the carriage walls, through slots 32 in the auxiliary lever section 18 and through a pin hole 33 in the section 17. By this arrangement the pin 27 establishes a fixed relation between the carriage 16 and the main section 17, so that the pin 27 constitutes a fulcrum for said main section converting the same into a lever of the second order exerting its force through the pin 24 and rollers 24^a against the walls of the slots 25 and thereby rocking the auxiliary lever 18, which is permitted freedom of movement on its fulcrum 19 by reason of the slots 32 in said auxiliary lever.

On the other hand, the pin 27 may establish a rigid relation between the main lever section 17 and the auxiliary section 18, so that the same will jointly constitute a lever of the first order rocking on the fulcrum 19 only, for which purpose pin holes 28 are formed in the walls of the section 18, a pin hole 29 is formed in the main section 17 to be brought into alignment with the holes 28, and slots 30 are formed in the walls of the carriage 16. Thus, as the unitary lever rocks on its fulcrum 19, the pin 27 may have play in the said slots 30 of the carriage.

Ordinarily the direct leverage will suffice, but an increased power, with a slower speed 50 of the carriage, may be obtained by compounding the leverage in placing the pin 27 in the upper position shown in Figs. 3, 4 and 5.

Instead of fastening the sector to the platform of the well, I provide an improved brace with means to detachably engage the same with the drill rod and with the sector. The brace, indicated generally by the numeral 34, rises at one end and has an offset 60 34^a which receives a head 35 raised to receive the coupling of the drill rod, so that the brace lies snugly against the said drill rod. The opposite end of the brace comprises diverging side arms 36 and a central 65 arm 37. The arm 37 is braced by a diagonal

bar 38 riveted to the brace 34 at the rise thereof and inclining to a point adjacent to the outer end of the arm 37 to which it is riveted or otherwise secured as at 38^a. The head 35 is adjustable, being formed with a slot 35^a which receives a bolt 39. The outer ends of the arms 36 are formed with hook members 40, and the ends of the sector are received between said hooks and studs or equivalent elements 41 on the said arms, 75 said studs presenting shoulders at the side thereof opposite the hooks 40. On the outer end of the arm 37 a similar hook 40^a is formed, and the central portion of the sector is received between said hook and the shoulder 41^a presented by the adjacent end of the rod 38.

I desire to explain further with respect to the movements to be imparted by the lever devices that in addition to the direct and indirect actions described, a modification of the movement imparted by the single lever is possible since the stroke thereof may be varied to give either a full stroke for advancing the distance of a tooth at one time, 90 or a stroke imparting movement the distance of half a tooth.

Having thus described my invention, what I claim as new and desire to secure by Letters Patent, is:

1. A wrench jack including a carriage adapted to travel on the wrench sector, a lever mounted on the carriage and pawls on the lever to engage the wrench sector, said lever comprising a main lever and an auxiliary lever, the latter carrying the said pawls; together with means to connect said levers to operate in unison as a single lever or to compound the leverage and cause the main lever to relatively rock the auxiliary lever. 100

2. In a jack, a carriage, a lever comprising a main and an auxiliary lever and means to connect said levers to operate in unison as a single lever or to connect the levers so that the main lever rocks the auxiliary lever relatively to the main lever; together with means to actuate the carriage by the movements of the said lever. 110

3. In a jack, a carriage, a lever comprising a main and an auxiliary lever, means to fulcrum the auxiliary lever, and means to lock the levers together to rock as a single lever on said fulcrum, or to separately fulcrum the main lever and rock the auxiliary lever on the first fulcrum by movements of the main lever on its fulcrum; together with means to actuate the carriage by the movements of the said lever. 115

4. A jack comprising a carriage, a main lever, an auxiliary lever fulcrumed on the carriage, pawls on said auxiliary lever to engage a rack, means forming a slot and pin connection between the levers, and means adapted to fulcrum the main lever on the 120 125 130

auxiliary lever and cause the slot and pin connection to actuate the auxiliary lever or to rock the levers to move as a single lever on the fulcrum of the auxiliary lever.

5. A well jack including a carriage, a lever fulcrumed on said carriage, and a pair of pawls pivoted on said lever at opposite sides of its fulcrum for engaging a rack, each of said pawls comprising a dog in fixed relation to the pawl and a dog pivoted on the pawl.

6. In a wrench of the class described, a

sector and a brace to detachably brace the sector against a drill rod, the said brace comprising a body presenting arms and a head extending in the opposite direction from the arms and having a recess to engage a drill rod, said head being adjustable upon the brace, the said arms having hooks at their outer ends and having members inward from the hooks and spaced from the latter a distance to receive the sector.

HARRY E. BROWN.
